UNITED STATES PATENT OFFICE.

WILLIAM B. SMITH, OF KANSAS CITY, MISSOURI.

DOOR-HANGER.

SPECIFICATION forming part of Letters Patent No. 665,036, dated January 1, 1901.

Application filed November 27, 1898. Serial No. 738,389. (No model.)

To all whom it may concern:

Be it known that I, WILLIAM B. SMITH, of Kansas City, Jackson county, Missouri, have invented new and useful Improvements in 5 Car-Door Hangers, of which the following is a specification.

My invention relates to improvements in car-door hangers; and the object of the invention is to produce a car-door hanger that 10 shall be strong, simple, reliable, and inexpensive of manufacture.

Reference is had to the accompanying drawings, in which—

Figure 1 is an elevation of a car-door in 15 closed position provided with my hangers. Fig. 2 is a front elevation of one of my improved hangers, showing also one of the track-bar sockets, a portion of the track-bar, and a corner of the car-door to which the hanger 20 is secured. Fig. 3 is a cross-section on the dotted line II II of Fig. 1. Fig. 4 is an elevation of the upper portion of the inside face of one of the hangers. Fig. 5 is a side elevation of the bracket supporting the central portion of the track-bar, showing the track-bar in section. Fig. 6 is a side elevation of one 25 of the terminal track-bar sockets.

The door 1 is suspended by the hangers 2 from the preferably-cylindrical track-bar 3, 30 which is secured to the side of the car by means of the end socket-supports 4 and the central bracket 5.

Hangers 2 are made right and left hand, and consist, mainly, of a flat portion 6, bolted 35 to the outside of the door, and, at the upper corners, of an inwardly-projecting box or frame 7, the outer wall of which is provided with a vertical slot 16 and the inner wall with a circular opening 18, communicating with 40 two opposite open slots or extensions 17. Two concave antifriction-rollers 8 and 9, provided with projecting axial studs 10, are arranged inside of said box or frame 7, the studs 10 lying within slots 16 and 17, the rollers 8 and 45 9 having been inserted into frame 7 through opening 18. When the hangers 2 are assembled upon track-bar 3, said rollers are

held separate from each other by said track-bar and are thereby prevented from leaving frame 7.

Track-bar 3 is supported at each end by a socket-piece 4, the closed side of one of said socket-supports being shown in Fig. 6. The base of each of the socket-supports 4 is provided with a point 14, adapted to enter the 55 side of the car and more firmly to hold the socket-support in position. Said socket-supports and the bracket 5 are screwed or bolted to the car.

The central track-bar bracket is shown in 60 Fig. 5 and has the same form as socket-supports 4, excepting that the opening for the track-bar extends entirely through its body.

Having described my invention, what I claim as new, and desire to secure by Letters 65 Patent of the United States, is—

In a car-door hanger, the combination of a cylindrical track-bar, a pair of socket-supports secured to the car and embracing the ends of said track-bar, track-bar-supporting 70 brackets intermediate of said socket-supports, and a pair of door-hangers secured respectively to the upper corners of the car-door, each hanger consisting of a flat body portion adapted to be secured to said door, and an 75 integral upward and inwardly extending hollow frame or box, the outer wall of which is provided with a vertical slot and the inner wall of which is provided with a central circular opening and opposite open slots communicating therewith and registering with said vertical slot, and two concave antifriction-rollers arranged in said frame or box and having axial projecting studs engaging said slots of said frame or box, and separated from 80 each other by said track-bar, substantially as described.

In testimony whereof I affix my signature in the presence of two witnesses.

WILLIAM B. SMITH.
